UNITED STATES PATENT OFFICE.

HARLEY D. PENNINGTON, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

PIPE-WORKING MACHINE.

Application filed June 9, 1923. Serial No. 644,314.

This invention relates to pipe-working machines, and is particularly directed toward a pipe-rounding mechanism which is conveniently used in connection with a pipe-threading machine. I provide means for rotating the pipe and a rounding die which engages the pipe as it is rotated. The die is made in a plurality of parts and the parts are simultaneously movable toward the pipe. This prevents the pipe from striking one of the rounding dies during operation, and also gives a superior rounding action. The rounding dies are mounted on a carriage which may be moved back and forth as the pipe is rotated, thus working the metal in the pipe and imparting true roundness.

In the accompanying drawings, there is shown, for purposes of illustration only, one embodiment of the present invention, it being understood that the drawings do not define the limits of the invention, as changes may be made in the construction and operation therein disclosed without departing from the spirit of the invention or scope of my broader claims.

In the drawings:

Figure 1 is a top plan view of a threading machine embodying my invention;

Figure 2 is a side elevation of the machine;

Figure 3 is a transverse vertical sectional view taken on the line III—III of Figure 1;

Figure 4 is a view partly in elevation and partly in section, the section being taken on the line IV—IV of Figure 1;

Figure 5 is a horizontal view of a portion of the apparatus illustrating a drive mechanism for shifting the pipe rounding carriage;

Figure 6 is a side elevation of the split nut, for engagement with the lead-screw, and parts associated therewith;

Figure 7 is a sectional view on the line VII—VII of Figure 6;

Figure 8 is a detail view showing the two halves of the split nut in section;

Figure 9 is a detail sectional view of the spring-actuated detent for the split nut operating means;

Figure 10 is a view partly in section and partly in elevation of the rounding mechanism and operating parts associated therewith;

Figure 11 is a sectional view on the line XI—XI of Figure 10.

Referring to the drawings, the machine 55 may comprise, as usual, a bed A, at one end of which is mounted a housing B in which is contained the means for gripping and rotating the pipe and for actuating the lead-screw, including the change speed mechanism. 60 Upon the bed A is also mounted a reciprocable carriage C which carries the threading die, rounding die, cutting-off knife, and other associated parts.

Referring particularly to Figures 1 to 4 65 inclusive, a barrel 2 for receiving the pipe is suitably journaled for rotation in the housing B. Mounted upon the forward end of the barrel 2 is a chuck 3, for gripping the pipe so it may be rotated.

Mounted upon the top of the housing B is the main driving motor 23 for rotating the barrel 2 and actuating a lead-screw to be hereinafter described. The shaft of the motor 23 carries a pinion 24 meshing with a gear 25, the latter driving a gear 26 mounted upon one end of a shaft 27 journaled in the housing B and carrying a pinion 28 meshing with a gear 29 on a second shaft 30 parallel to the shaft 27 and carrying a pinion 31 80 in driving engagement with a large gear 32 carried by the barrel 2.

The gear 32 drives a gear 33 mounted upon a shaft 34, the latter having mounted upon one end thereof a bevel gear 35 meshing with a similar bevel gear 36 on the end of a shaft 37. The shaft 37 carries a worm 38 which engages a worm wheel 39 on a shaft 40. The shaft 40 carries a pair of spaced gears of different sizes and constituting elements of a 90 change-speed mechanism for actuating the hereinbefore referred to lead-screw. This change-speed mechanism may also comprise gears of different sizes and mounted on a shaft 46 carried by spaced rocker-arms 47. 95 These rocker-arms are journaled upon a shaft 49. This change speed gearing is effective for driving the shaft 49 at desired speed. The arm 47 is provided with an integral extension 60 which extends through an opening in the front of the housing B and is provided with a barrel portion 61 in which is mounted a spring-pressed pin 62 adapted to engage any one of a plurality of holes 63 in the housing B to hold the change-speed mechanism in the desired adjusted position.

The shaft 49 is in alignment with a lead-screw 64 and is operatively connected to the

latter by a suitable coupling 65. The lead-screw 64 is adapted to be operatively connected to the carriage C by a clutch which is illustrated in detail in Figures 6 to 9 inclusive. This clutch comprises a split-nut 66, the two halves of which are shown in section in Figure 8 and which are mounted for sliding movement towards and from each other in a suitable supporting housing 67 integral with and projecting from the front of the carriage C. This supporting housing 67 may be provided with a suitable cover plate 68 secured thereto by screws 69. Each half of the nut 66 has an opening 70 extending there-through for receiving a pin 71. The pins 71 extend at their opposite ends through cam slots 72 in a pair of cam plates 73 arranged at opposite ends of the housing 67. Each of these cam plates is provided with a central opening for receiving the lead-screw 64. The cam plates 73 are maintained upon the pins 71 by means of washers 74 and cotter pins 75 carried by the respective ends of said pins 71.

25 Journaled in brackets 76 carried by the bed A is a shaft 77 which is rectangular in cross-section. Slidably mounted upon the shaft 77 is a bushing 78, the latter being journaled in the housing 67 and projecting at opposite ends therefrom. Mounted upon each projecting end of the bushing 78 and secured thereto by a set screw 79 is a rocker-arm 80, one of said rocker-arms being provided with an integral handle portion 81.

30 Each rocker-arm 80 is curved to extend around the front and over the top of the lead-screw 64 and is pivotally connected at its upper end to the adjacent cam plate 73 by means of a pin 82 fixed in the cam plate and having a threaded end portion to extend through an opening in the lever 80. Mounted upon the threaded end portion is a nut 83. One of the cam plates 73 is provided in its peripheral edge with three spaced recesses or depressions

35 84, 85 and 86 adapted to be engaged by a spring actuated ball detent 87 mounted in the housing 67. It will be noted by reference particularly to Figure 7, that each slot 72 in the cam plates 73 comprises a portion which is concentric with the axis of the lead-screw and another portion which is eccentric thereto.

40 The operation of the clutch above described is as follows: In Figure 7 the ball detent 87 is shown in engagement with the recess 84. In this position of the parts, the halves of the slit-nut 66 are moved out of engagement with the lead-screw 64 because the pins 71 are located in the concentric portions of the slots

45 72. Rotation of the lead-screw will, therefore, have no effect upon the carriage C. If the handle 81 is actuated to rotate the cam plates 73 in a counter clockwise direction (Figure 7) until the ball detent 87 engages the intermediate recess 85, this being the neu-

tral position of the parts, the halves of the split-nut will remain in the open position because this movement of the cam plates does not carry the pins 71 out of the concentric portions of the slots 72. However, when the handle 81 is further actuated to rotate the cam plates 73 into a position in which the ball detent 87 drops into the recess 86, the split-nut 66 is closed upon the lead-screw 64, the latter is operatively connected to the carriage C and rotation of the lead-screw will cause movement of said carriage towards or from the housing B, depending upon the direction in which the lead-screw is rotated.

50 The bed A is provided with suitable parallel tracks 88 and the carriage C may be supported for reciprocation on the bed by means of rollers 89 which engage said tracks and are journaled by means of roller bearings 89' upon fixed pins 90 carried by the carriage 85 or the carriage may directly engage said tracks or the bed.

55 The carriage C is provided at each side thereof with a downwardly facing rack 95 adjacent the corresponding track 88. Journaled in the bed A and extending transversely thereof is a hollow shaft 96 having mounted thereon a pair of pinions 97 engaging the racks 95.

60 For moving the carriage C on the bed A independently of the main motor 23, an additional motor 98 is provided. Referring to Figure 1, the shaft of the motor 98 is provided with a worm 99 in driving engagement with a worm wheel 100 on a shaft 101. The shaft 101 carries a bevel pinion 102 engaging a bevel gear 103 journaled loosely upon the hollow shaft 96. The bevel gear 103 is integrally formed on one end of a sleeve 104 upon the other end of which is formed a clutch member 105. A cooperating clutch member 106 is formed on a collar 107 keyed to the hollow shaft 96 for sliding movement thereon.

65 The collar 107 is operatively connected to the rock shaft 77 by means shown in detail in Figure 5. This means comprises a lever 108 pivoted intermediate its ends at 109 and pivotally connected at one end to a pin 110 carried by a member 111 engaging in a peripheral groove in said collar 107. The lever 108 is pivotally connected at its other end to a pin 112 carried by a sleeve 113 slidably mounted upon a rod 114. The rod 114 is pivotally connected at one end to the bifurcated end of a rocker-arm 115 carried by the shaft 77. The opposite end of the rod 114 is screw-threaded and has mounted thereon nuts 116 engaged by a washer 117. Mounted loosely upon the rod 114 intermediate the sleeve 113 and the washer 117 is a washer 118 surrounding the rod 114 intermediate the washers 117 and 118 is a coil spring 119.

70 The rod 114 may assume any one of three

positions corresponding to the open, neutral and closed positions of the split-nut 66. The full line position of the rod 114 shown in Figure 5 and represented by the reference character *a* corresponds to the closed position of the nut 66, in which position of said nut the ball detent 87 engages the recess 86. When the handle 81 is moved to the neutral position in which the detent 87 engages in the recess 85, the rod 114 assumes the position represented by the reference character *b* in Figure 5. The movement of the rod 114 from position *a* to position *b* has no effect upon the collar 107 and clutch member 106 carried thereby since the rod 114 slides freely through the sleeve 13. This movement of the rod 114, however, brings the washer 118 into the dotted line position thereof shown in Figure 5, in which position said washer engages the end of the sleeve 113. In this neutral position of the nut 66, the carriage C is disconnected both from the main motor 23 and from the auxiliary motor 98 and the carriage C may be moved on the bed A by 25 manually operated means to be hereinafter described. When the handle 81 is actuated to open the nut 66, which position of the parts is illustrated in Figure 7 wherein the detent 87 is shown in engagement with the recess 84, the rod 114 assumes the position indicated by the reference character *c* in Figure 5. The movement of the rod from the position *b* to the position *c* causes the lever 108 to be swung into the dotted line position thereof indicated in Figure 5, thereby moving the clutch member 106 into engagement with the cooperating clutch member 105 on the sleeve 104. By providing the spring 119 and loose washer 118, it will be apparent that the clutch member 106 is yieldingly actuated into engagement with its cooperating clutch member 105, thereby enabling said clutch members to interengage without danger of breakage of the teeth of said clutch members even though the clutch member 105 be rotating. When the clutch member 106 is brought into operative engagement with the clutch member 105, the motor 98 is operatively connected to a carriage C through the hollow shaft 96, pinions 97, and racks 95, and at the same time the main motor 23 is disconnected from the carriage C by reason of the fact that the nut 66 is at this time in the open position.

As already stated, when the handle 81 is in the neutral position thereof, both motors 23 and 98 are disconnected from the carriage C and the latter may at this time be moved on the bed by manually operated means. This means comprises a rod 120 sliding and rotating in the hollow shaft 96 and having on one end thereof an operating handle 121. The normal position of the rod 120 and handle 121 is the dotted-line position of these parts indicated in Figure 5. The rod 120 carries a pinion 122 adapted to engage a gear 123 on a shaft 124. The shaft 124 carries a second gear 125 meshing with one of the pinions 97 on the hollow shaft 96. The normal position of the pinion 122 is the dotted-line position thereof indicated in Figure 5 and corresponding to the dotted-line position of the rod 120 and handle 121. In this position of the pinion 122, it is out of engagement with the gear 123. After the handle 81 has been moved to neutral position, if it is desired to move the carriage C manually by the means just described, it is only necessary to push the handle 121 inwardly to cause the pinion 122 to engage the gear 123, whereupon rotation of the handle 121 will cause rotation of the shaft 124 and consequently rotation of the hollow shaft 96 by reason of the engagement of the gear 125 with the pinion 97. Rotation of the shaft 96 causes movement of the carriage C on the bed A by reason of the engagement of the pinions 97 with the racks 95.

The carriage C may be provided with a suitable threading die 126, indicated in dotted outline in Figure 2, and also a suitable cutting-off knife 127, indicated in Figure 4.

It is customary in this art to provide a threading machine with a suitable rounding mechanism. Such mechanism usually comprises a rounding die made in two halves; the lower half being fixed and the upper half being movable. An objection to the mounting of the rounding die in this manner is that the end of the incoming pipe is apt to strike the lower half of the rounding die. A feature of the present invention is the provision of novel means for actuating the rounding die, whereby both the upper half and the lower half of the die may be actuated into and out of operative position. The rounding mechanism of the present invention is shown in detail in Figures 4, 10 and 11. Referring to these figures, the lower half 128 of the rounding die is operatively connected to the upper half 129 thereof. Said lower half 128 is carried by a lower crosshead 130. Vertical bars 131 have their lower ends fastened to the opposite ends of said lower crosshead 130 and their upper ends fastened to the opposite ends of an upper crosshead 132. The vertical bars 131 slidably engage the inner edges of the legs of an inverted U-shaped supporting standard 133. Cheek-plates 134 are fastened to opposite sides of the crossheads 130 and 132 at the ends thereof and engage the opposite side edges of the legs of said standard 133, whereby to guide the vertical reciprocating movements of said vertical bars 131 and connecting crossheads 130 and 132. The upper half 129 of the rounding die is fastened in the channel of a sliding crosshead 135. This crosshead at its opposite ends engages the opposite edges of the vertical bars 131, whereby the reciprocating movements of said crosshead are guided. Intermediate the top cross-

head 132 and the sliding crosshead 135 is arranged another sliding crosshead 136. Extending transversely through the central portion of the crosshead 136 is a nut 137 which 5 is fixed in said crosshead and provided at its opposite ends with trunnions 138. The nut 137 is provided with a vertical screw-threaded bore in engagement with the screw-threaded lower end of a vertical shaft 139. The 10 shaft 139 is provided with an integral bearing 140 whereby said shaft is journaled in the upper crosshead 132 but fixed against longitudinal movement therein. Above the bearing 140 the shaft is provided with a screw-threaded portion 141 engaged by a nut 142 having an operating handle 143. The shaft 139 at its upper end extends through and is keyed to a bushing 144 journaled in the upper portion of the standard 133, whereby said 15 shaft may be moved longitudinally in said bushing 144. The bushing 144 has integral with its upper end a bevel gear 145 which is engaged by a bevel pinion 146 carried by a horizontal shaft 147 journaled in bearings 148 carried by said standard 133, said shaft 147 being provided with a suitable operating handle 149. The sliding crossheads 135 and 136 are operatively connected by two pairs of toggle levers 150, each pair of toggle levers 20 being pivoted at one end upon a trunnion 151 carried by the crosshead 135 and upon a trunnion 138 of the nut 137. The two members of each pair of toggle levers 150 are pivotally connected by a pivot pin 152. A link 153 is 25 pivotally mounted at one end upon each pivot pin 152, each of said links being pivoted at its opposite end to an arm of a bell-crank lever 154. The bell-crank levers 154 are pivoted at the angle thereof upon a pivot pin 155 carried by the standard 133. The other arms of the bell-crank levers 154 are connected by a transverse pin 156 and a link 157 is journaled at one end upon said pin 156 intermediate said arms and at its opposite end is pivotally 30 connected to the upper end of a piston rod 158, the piston 159 of which operates in a fluid-pressure cylinder 160.

The operation of the rounding mechanism above described is as follows: The normal 35 operative open position of the two halves 128 and 129 of the rounding die is shown in full lines in Figures 4 and 10. The position of a pipe inserted between said parts of the rounding die is indicated in dash and dot lines in these figures. It will be seen that the lower half 128 of the die, as well as the upper half thereof, is out of the path of the incoming pipe so that the latter will not strike against said part. When it is desired 40 to engage the pipe by the parts of the rounding die either for the purpose of performing the rounding operation or for the purpose of cutting off the end of the pipe, fluid pressure will be admitted to the cylinder 160 to actuate the toggle levers 150 to straighten the latter.

This operation will cause the upper crosshead 132 to be moved upwardly until the nut 142 on the screw-threaded portion 141 of the shaft 139 engages the underside of the upper portion of the standard 133 and will also cause the sliding crosshead 135 to move downwardly. As soon as the nut 142 engages the underside of the top portion of the standard 133, further upward movement of the upper crosshead 132, and consequently of the lower 45 half 128 of the rounding die is arrested, so that further straightening of the toggle levers 150 will result in movement only of the upper half 129 of the rounding die. The nut 142 may be adjusted upon the screw-threaded portion 141 in order to vary the extent of upward movement of the crosshead 132. The hand-wheel 149 affords means for adjusting the position of the crosshead 136 whereby the path of travel of the upper half 129 of the 50 rounding die may be shifted. This hand-wheel 149 also affords means for manual adjustment of the pressure of the rounding die upon the pipe after the toggle levers 150 have been straightened by the fluid pressure actuating means. When it is desired to round a portion of the pipe, the fluid-pressure actuating means for operating the rounding die may be operated to produce the desired clamping pressure of said rounding die upon the pipe, 55 whereupon the handle 81 may be actuated to throw in the clutch for the motor 98. The latter motor may be now actuated to reciprocate the carriage C back and forth upon its bed A to produce the desired rounding. After the pipe has been cut off and rounded, the rounding die may be opened and the carriage moved by means of the motor 98 to the approximate position thereof to begin the threading operation whereupon the lever 81 60 may be moved through its neutral position to disconnect the motor 98 from the carriage and then into a position to close the nut 66 upon the lead-screw. After this has been done, the operation of the carriage C will be under the control of the main motor 23. It will be seen, therefore, that the motor 98 may be utilized to move the heavy carriage C during the rounding operation and to properly position the carriage preliminary to the cutting-off 65 operation, the rounding operation or the threading operation. Furthermore, it has already been pointed out that the carriage may be manually moved by means of the handle 121 and shaft 120.

I claim:

1. In a pipe-working mechanism, means for rotating a pipe a rounding die having a plurality of parts, means for moving said parts inwardly toward each other to engage the rotating pipe and outwardly away from each other, and adjustable means for limiting the inward movement of one of said parts, substantially as described.

2. In a pipe-working mechanism, means for

rotating a pipe a two-part rounding die, means for moving said parts inwardly toward each other to engage the rotating pipe and outwardly away from each other; and adjustable means for limiting the inward movement of one of said parts, substantially as described.

3. In a pipe-working mechanism, means for rotating a pipe a two-part rounding die, 10 means for moving said parts inwardly toward each other to engage the rotating pipe and outwardly away from each other, means for adjusting the position of the path of travel of one of said parts, and adjustable 15 means for limiting the inward movement of the other of said parts, substantially as described.

4. In a pipe-working mechanism, a frame having a window therein, a crosshead 20 slideable in said window, a two part rounding die having one of its parts connected to said crosshead to be moved thereby, a second cross-

head slideable in said window, a screw journaled in the first crosshead and having threaded engagement with the second crosshead whereby to adjust the distance between said crossheads, toggle means connecting the second crosshead to the other part of the rounding die, means for operating said toggle means, and an adjustable stop carried by said screw and engageable with said frame for limiting the inward movement of the first die part when the toggle is operated, the path of the second die part being adjustable by means of said screw, substantially as described. 30

5. In a pipe working mechanism, a rounding die having a plurality of parts movable inwardly toward each other and outwardly away from each other, fluid actuated means for moving said parts and means for rotating a pipe engaged by the die. 40

In testimony whereof I have hereunto set my hand.

HARLEY D. PENNINGTON.
